WILLIAM ANSELM COATES, OF BROOKLANDS, AND WILLIAM BOURNE DALE, OF MANCHESTER, ENGLAND, ASSIGNORS TO WESTINGHOUSE ELECTRIC & MANUFACTURING COMPANY, A CORPORATION OF PENNSYLVANIA.

CIRCUIT INTERRUPTER.

Application filed November 11, 1919. Serial No. 337,194.

To all whom it may concern:

Be it known that we, WILLIAM ANSELM COATES, a subject of the King of Great Britain, and a resident of Brooklands, in the county of Chester, England, and WILLIAM BOURNE DALE, a subject of the King of Great Britain, and a resident of Old Trafford, Manchester, in the county of Lancaster, England, have invented a new and useful Improvement in Circuit Interrupters, of which the following is a specification.

Our invention relates to circuit interrupters and particularly to operating mechanisms for circuit interrupters in which a loose handle or operating member may not be held closed when abnormal conditions, such as an overload, prevail in the circuit.

20 The object of our invention is to provide a movable latch member, for a device of the above indicated character, that may be actuated at any position in its path of movement.

25 Circuit interrupters of the above indicated character comprise a lever which supports and actuates the movable contact members of the interrupter, a main operating lever which may be moved manually, by an electromagnetic device, or otherwise, when it is desired to close the interrupter, a latch which connects the operating lever to a toggle mechanism, or an intermediate lever by which the supporting lever is operated, and a tripping device for actuating the latch to disconnect the operating lever from the toggle mechanism or intermediate lever and thereby permit the supporting lever to move to the open position.

40 According to our invention, the operative point of connection of the tripping device with the latch, which connects the operating handle of the interrupter to its actuating mechanism, is so arranged that, under normal conditions, it remains in the same position, relative to the latch, throughout the whole range of movement of the latter, during the closing operation of the interrupter.

50 Figure 1, of the accompanying drawings, is a side view, partially in section and partially in elevation, of an oil-immersed circuit interrupter constructed in accordance with our invention; Fig. 2 is a view,

similar to a portion of Fig. 1, of a modified form thereof, and Fig. 3 is a view, similar to Fig. 2, of a further modified form of interrupter embodying our invention.

A main movable contact member 1 is connected, by means of a vertical link 2, to a lever 3 pivoted on a stationary pivot pin 4, and is adapted to move into and out of engagement with stationary contact members 5. A solenoid 6 is provided to close the interrupter and a tripping magnet 7 is provided to open the same.

Referring to Fig. 1, the lever 3 is connected, by toggle links 8 and 9, to a stationary pivot pin 10, on which is, also, pivoted an operating lever 11 that is connected, by a link 12, to an armature or plunger (not shown) of the closing solenoid 6. Sufficient clearance is provided for the link 12, in the switch casing and in the solenoid 6 to permit the lever 11 to rotate about the pin 10. A latch member 13 is pivoted to a pivot pin which connects the toggle levers 8 and 9 to each other, and a hook 14 is adapted to engage a pin 15 which joins the lever 11 to the link 12.

The tripping magnet 7 is provided with an armature 16 which is biased away from the magnet by a spring 17 and is connected to the latch 13 by a link 18. In the normal de-energized position of the tripping magnet 7, a pivot pin 19, connecting the armature 16 and the link 18, is coaxially related to the pivot pin 10 but is not attached thereto. When the latch 13 is in holding relation to the toggle link 8 and the operating lever 11, these three parts will all move around the pin 10, and, therefore, the link 18 and the pivotal connection of the link 18 with the latch 13 will also move around a centre co-axial with the pin 10 throughout the whole range of movement of the parts during the operation of closing the interrupter.

Consequently, the pivot pin 19 will remain in the same position relative to the latch during the closing movement.

In operation, the parts are biased to the open position, shown in broken lines in the drawing, by reason of the weight of the movable contact member 1, the link 2 and the lever 3. The operating lever 11, the link 12 and the plunger or armature of the closing solenoid 6, are raised, by means of a

spring 20, to a position in which the latch 13 engages the pin 15 on the operating lever 11. When it is desired to close the interrupter, the solenoid 6 may be energized to move the link 12 downwardly, thereby causing, by means of the latch 13, the toggle links 8 and 9 and a portion of the main switch lever 3 to move downwardly to the position, shown in full lines, wherein the switch is closed. During the closing movement, the spring 20, having one end attached to a stationary support, as on the casing of the interrupter, and its other end attached to the link 11, is put under tension, and the link 18, connecting the latch 13 with the armature 16 of the tripping magnet, turns on the pin 19, but the armature 16 remains in the same position.

If the tripping magnet 7 is energized when the interrupter is closed, or during any part of the closing movement, the armature 16 will be attracted and, by means of the link 18, release the latch 13 from the pin 15, thereby disconnecting the toggle links 8 and 9 from the operating lever 11. If the interrupter is then in the closed position the weight of the members 1, 2 and 3 will cause the interrupter to open. When the interrupter is open, the lever 11 is disconnected from the toggle links 8 and 9.

A latch 21 is pivoted to a fixed pin 22 and is provided with a spring 23 which causes it to engage a pin 24 on the link 12, when the latter has been moved to its lowest position, in order that the interrupter shall remain closed when the closing solenoid 6 is deenergized. To open the interrupter, the latch 21 is manually turned against the force of the spring 23 to release the pin 24, whereupon the weight of the movable parts, assisted by the spring 20, will cause the interrupter to open and the toggle links 8 and 9 to assume the position shown in broken lines. The operating lever 11, the latch 13 and the associated parts follow in the upward movement.

After the interrupter is opened, by the operation of the tripping magnet 7, the latch 13 is disconnected from the operating lever 11 and permits the toggle levers 8 and 9 to assume the open position, as above described. The operating lever 11 and the link 12 will, however, remain in the position shown in full lines until the latch 21 has been released; whereupon, the spring 20 will raise the operating lever 11 and, if the armature 16 has, meanwhile, been released by the tripping magnet, the pin 15 will re-engage the hook 14 of the latch 13 to permit the interrupter to be again closed by energization of the closing solenoid.

In Fig. 2, which shows a similar mechanism, the latch 13 is connected to the armature or plunger of the tripping magnet 7 by a flexible member 25 that passes

through an opening 25* in the pin 10*. The operative point of connection between the tripping device and the latch 13 is, in this form, the fixed pivot pin 10* which is the center of movement of the toggle link 9, 70 operating lever 11 and latch 13, as above described. The operation of the device of this modification is similar to that of the mechanism above described and will be understood without further description. 75

Referring to Fig. 3, an operating lever 26 is pivoted to a fixed pivot shaft or pin 27 and is connected, by a link 28, to the armature or plunger of the closing solenoid 6*. An intermediate lever 29 is pivoted coaxially with the operating lever 26 and is provided with a projection 30 adapted to engage a roller 31 on the lever 3*. Connection between the operating lever 26 and the intermediate lever 29 is effected by means of a latch 32 which normally engages a projection 33 on the intermediate lever 29. The armature 16* of the tripping magnet 7* is connected, by a link 34, to a movable bar 35 supported, by parallel links 36 and 37, from a stationary member 40, the bar 35 having an edge or surface 38 which is shaped to the arc of a circle having its center coincident with the axis of the pin 27. Since the intermediate lever 29, the operating lever 26 and the latch 32 move around the pivot pin 27, during the closing operation of the interrupter, it will be clear that the abutting surface 38 of the bar 35, by reason of its curvature, is in position to engage the latch 32, throughout the whole range of movement of said latch, during the closing operation of the interrupter. The interrupter is in its closed position, as shown in full lines. The combined weight of the movable member 1, link 2 and the lever 3 biases the interrupter to its open position, in which the intermediate lever 29 occupies the position shown in broken lines in the drawing. The spring 20*, connected to the operating lever 26, corresponds to the spring 20, as shown in Fig. 1. The spring 39 causes the latch 32 to engage the projection 33 of the intermediate lever 29, when the operating lever 26 is raised, and the latch 21 corresponds to the latch 21*, as shown in Fig. 1, to perform the same function of holding the interrupter in its closed position.

In operation, assuming the interrupter to be open, the operating lever 26 to be in its raised position and the latch 32 connecting it to the intermediate lever 29, a movement of the lever 26 to the position shown in full lines, by energizing the closing solenoid 6*, will turn the lever 29 which will close the interrupter through the projection 30. The lever 26 is held, in the position shown, by means of the latch 21*. By releasing the latch 21*, the weight of 120

the bridge piece 1, and its associated parts, will open the interrupter, the spring 20^a causing the lever 26 to follow the opening movement. When the tripping magnet 7^b is energized, the bar 35 will be lifted and, thus, moving away from its support 40, will disengage the latch 32 from the lever 29 to permit the weight of the member 1, and its associated parts, to open the interrupter. If the interrupter is in the open position, the latch 32 being disengaged, the operating lever 26 will be disconnected from the intermediate lever 29, and the interrupter cannot be closed.

15 While we have shown and described particular forms of our invention, changes may be effected therein without departing from the spirit and scope thereof, as set forth in the appended claims.

20 We claim as our invention:

1. The combination with two independently movable members, and latching means for holding said members together during a simultaneous movement thereof, of means 25 remotely disposed with respect to said members for releasing said latching means at any position in its path of movement, and flexible connecting means between said releasing and said latching means.

20 2. The combination with a pivoted arm having a movable latch member mounted thereon at a point removed from the pivot thereof, and remotely disposed releasing means for said latch member, of a member 35 connected between said latch member and said releasing means having a portion adapted to move about an axis coincident with the pivotal axis of said arm.

3. The combination with a pivoted arm 40 having a movable latch member mounted thereon at a point removed from the pivot thereof, and remotely disposed releasing means for said latch member, of a pair of end-to-end related links connected between 45 said latch member and said releasing means, the point of joinder between said links being normally on an axis coincident with, but independent of, the axis of said pivoted arm.

4. The combination with a pivoted arm 50 having a movable latch member mounted thereon at a point removed from the pivot thereof, and remotely disposed releasing means for said latch member, of a pair of end-to-end related links connected between 55 said latch member and said releasing means, the point of joinder between said links being normally on an axis coincident with, but in-

dependent of, the axis of said pivoted arm and movable out of coincidence therewith during the releasing action.

60

5. In a circuit interrupter, the combination with two movable members, and latching means co-operating therebetween in order that said members may move together, of a magnetically actuated member for releasing said latching means at any position in its path of movement.

65

6. In a circuit interrupter, the combination with two movable members, and latching means co-operating therebetween in order that said members may move together, and means responsive to predetermined conditions in the circuit for releasing said latching means at any position in its path of movement.

70

7. In a circuit interrupter, the combination with two movable members, and latching means co-operating therebetween in order that said members may move together, of a magnetically actuated member connected to the latching means and adapted to release said means at any position in its path of movement.

75

8. The combination with a pivoted arm having a movable latch member mounted thereon at a point removed from the pivot thereof, a remotely disposed releasing means for said latch member, and a member connected between said latch member and said releasing means having a portion adapted to move about an axis coincident with the pivotal axis of said arm, of a second latching means adapted to normally secure the aforesaid mechanism in its operative position.

80

9. The combination with a pivoted arm having a movable latch member mounted thereon at a point removed from the pivot thereof, a remotely disposed releasing means for said latch member, and a member connected between said latch member and said releasing means having a portion adapted to move about an axis coincident with the pivotal axis of said arm, of a second latching means adapted to normally secure the aforesaid mechanism in its operative position.

85

10. The combination with a pivoted arm having a movable latch member mounted thereon at a point removed from the pivot thereof, a remotely disposed releasing means for said latch member, and a member connected between said latch member and said releasing means having a portion adapted to move about an axis coincident with the pivotal axis of said arm, of a second latching means adapted to normally secure the aforesaid mechanism in its operative position, the actuation of the first named latch permitting said pivoted arm, the first named latch and said connecting member to move independently of said second named latch.

90

105 In testimony whereof, we have hereunto subscribed our names this 9th day of October, 1919.

WILLIAM ANSELM COATES.
WILLIAM BOURNE DALE.
